The ornamental design for a medical glove, as shown and described.

DESCRIPTION

FIG. 1 is a perspective view of a medical glove for the right hand in accordance with the invention;

FIG. 2 is a plan view of the back of the medical glove of FIG. 1;

FIG. 3 is a plan view of the front of the medical glove of FIG. 1; and,

FIG. 4 is an elevation view of the right side of the medical glove of FIG. 1.

The views of the medical glove for the left hand in accordance with the invention are mirror images of FIGS. 1-4.
